P. E. PAISLEY

PROJECTILE

Filed April 19, 1924

INVENTOR

P. E. Paisley
BY
W. F. Keefer.
ATTORNEY

UNITED STATES PATENT OFFICE.

PERL E. PAISLEY, OF BELLAIRE, OHIO.

PROJECTILE.

Application filed April 19, 1924. Serial No. 707,657.

To all whom it may concern:

Be it known that I, PERL E. PAISLEY, a citizen of the United States, residing at Bellaire, in the county of Belmont and State 5 of Ohio, have invented a new and useful Projectile, of which the following is a specification.

This invention relates broadly to projectiles, and more specifically to an anti-heat-10 nose for explosive-carrying high-speed artillery projectiles.

The primary object is to provide a projectile with a removable windshield having vents therein designed to allow the free 15 passage of air between said shield and the main body of the projectile in order to prevent heating of said projectile due to friction with the atmosphere.

A further object of this invention is to 20 provide a device of the character mentioned which will offer a minimum of resistance to the passage of the projectile through the atmosphere.

In describing my invention in detail, 25 reference is had to the accompanying drawings, in which—

Figure 1 is a longitudinal sectional view of an artillery projectile embodying my invention; and—

30 Figure 2 is a transverse section of the same on the line 2—2, Figure 1.

Referring to said drawings, in which like designating characters distinguish like parts throughout the several views, the numeral 35 1 indicates the main body portion of a projectile of ordinary type having an interior chamber 2 for the reception of an explosive.

Secured to the forward end of said projectile and completely covering its nose 3, is a shield or cap 4. Said shield is preferably screwed to said body 1, as by means of threads 5. The forward end of said shield is provided with an axial aperture 6 through which air is forced in the passage of the projectile through the atmosphere. After passing through said aperture the air expands within the relatively larger chamber 7 provided within said shield, and 45 thence passes outward through a plurality of vents 8 provided in said shield near the rear end thereof. If desired, the vents 8 may be directed outward through said shield at right angles with the axis of said projectile. However, in order to lessen the

resistance which the outgoing air affords to the passage of the projectile through the atmosphere, I prefer to direct said vents backward at an acute angle with the axis of the projectile, substantially as shown. 60 This construction also, by reason of the suction it affords in the passage of the projectile through the atmosphere, materially assists in evacuating said chamber 7 of its rarefied or expanded air. 65

Thus it will be understood that the air within the chamber 7 will, by reason of its expansion therein, be considerably cooler than the outside air which is compressed by impinging against the exterior surface 70 9 of said shield 4. And the cooler air within said chamber 7, constantly passing outward through the vents 8, maintains the nose 3 at a much lower temperature than would be the case if said shield were not 75 used.

I claim—

1. A windshield for an explosive-carrying projectile, having an aperture in the forward end thereof and a plurality of vents 80 toward the rear end thereof, said aperture and vents connecting the exterior of said windshield with an interior expansion chamber.

2. A windshield for an explosive-carrying projectile, having an aperture in the forward end thereof and a plurality of vents toward the rear end thereof, said aperture and vents connecting the exterior of said windshield with an interior expansion 90 chamber, said vents being directed outwardly and rearwardly at an acute angle with the axis of said windshield.

3. A windshield for an explosive-carrying projectile, having an aperture in the forward end thereof and a plurality of vents 95 toward the rear end thereof, said aperture and vents connecting the exterior of said windshield with an interior expansion chamber, said vents being directed outwardly and rearwardly at an acute angle with the axis of said windshield, said windshield being rigidly fastened to the nose of an explosive-carrying projectile. 100

4. The combination with an explosive-carrying projectile, of a windshield rigidly attached to said projectile and covering the nose thereof, said windshield being so shaped as to form an expansion chamber for air forward of and around said nose, 110

said chamber having connection with the exterior of said windshield by an axial aperture in the forward end of said windshield.

- 5 5. The combination with an explosive-carrying projectile, of a windshield rigidly attached to said projectile and covering the nose thereof, said windshield being so shaped as to form an expansion chamber 10 for air forward of and around said nose, said chamber having connection with the exterior of said windshield by an axial aperture in the forward end of said windshield and by a plurality of vents located 15 near the rear end of said windshield.

6. The combination with an explosive-

carrying projectile, of a windshield rigidly attached to said projectile and covering the nose thereof, said windshield being so shaped as to form an expansion chamber 20 for air forward of and around said nose, said chamber having connection with the exterior of said windshield by an axial aperture in the forward end of said windshield and by a plurality of rearwardly 25 directed vents located near the rear end of said windshield.

PERL E. PAISLEY.
